UNITED STATES PATENT OFFICE.

FRED S. WELCH, OF PONTIAC, MICHIGAN.

PRESSURE-GENERATING DEVICE.

1,218,233.

Specification of Letters Patent.

Patented Mar. 6, 1917.

Application filed August 25, 1915. Serial No. 47,322.

To all whom it may concern:

Be it known that I, FRED S. WELCH, a citizen of the United States, residing at Pontiac, county of Oakland, State of Michigan, have invented a certain new and useful Improvement in Pressure-Generating Devices, and declare the following to be a full, clear, and exact description of the same, such as will enable others skilled in the art to 10 which it pertains to make and use the same, reference being had to the accompanying drawings, which form a part of this specification.

My invention relates to pressure generating devices and a special object of my improvements is to combine with a sprayer an automatically acting gas pump actuated by internal combustion and in this way to produce and maintain a gas pressure in a receptacle. This pressure being the immediate liquid actuating means.

I accomplish this object in the device illustrated in the accompanying drawing which is an elevation partly in section of an apparatus embodying my invention, the electric circuits and apparatus being shown diagrammatically.

a is a tank capable of holding the considerable pressure used to actuate the liquid 30 which is to be sprayed upon trees. *b* is the pipe through which the liquid is impelled, this pipe opens toward the bottom of the tank *a* and is provided with a foot valve *c*. The air or gas in the space *d* above the liquid 35 *e* in the tank *a* is compressed to a considerable pressure. *f h j* is a pipe or passage extending vertically at *j* having an elbow at *f* and extending horizontally into a tank *a* at *h*. *g* indicates apertures formed through the 40 wall of the pipe *f h j* at the top of the portion *h* and just within the wall of the tank *a*. *i* is the combustion chamber. *o* is an inwardly opening check valve controlling the induction port to the combustion chamber *i*.

n represents a conventional priming device. *m* is a carbureter. *k* is a pipe connecting the carbureter with the induction port of the combustion chamber *i*. *q* is a diaphragm chamber connected on one side of the diaphragm by a small passage *q²* with the chamber *i* and on the other side by a pipe *t* with the space *d*. *p* is a sparking plug. *s* is a battery and the conventional spark producing electrical apparatus is represented diagrammatically, connecting the battery *s* and plug *p*. *q³* is a diaphragm in the chamber *q*.

r is a rod extending from the center of the diaphragm *q³* at right angles thereto and adapted to slide through an aperture through the wall of the chamber *q*. *r²* is a contact point with which the rod *r* is adapted to make contact to complete a circuit to cause a spark in the combustion chamber *i*. *u* is a spring adapted to put an adjustable pressure upon the rod *r*.

The operation of the above described device is as follows:

A little gasolene may be inserted in the combustion chamber *i* through the apparatus *n* and a small air pump may be fitted to said apparatus so that a combustible mixture under some pressure is created in the chamber *i*. The pressure due to the head of liquid in the tank *a* forces the diaphragm *q³* outward making contact at *r r²* and causing a spark in the combustion chamber *i* which ignites the mixture therein. The pressure rises in the chamber *i* forcing the liquid through the pipe *f h j* forcibly into the tank *a* and when the liquid has passed the aperture *g* part of the gases under pressure pass through said apertures and rise through the liquid to the space *d*. The liquid is carried forward by its inertia, and the gases in the pipe *f h j* and the chamber *i* are cooled, thus producing a partial vacuum in the chamber *i*, which causes the valve *o* to open and draws a combustible mixture through the carbureter *m*. The liquid returning in the pipe *f h j* compresses the mixture in the combustion chamber *i* and again presses out the diaphragm *q³* completing the electric circuit, the charge is again ignited in the chamber *i* and the operation is continually repeated. By this means any desired pressure may be created and maintained in the space *d*. The liquid in the pipe *f h j* forms a piston having considerable inertia.

What I claim is:

1. In a sprayer, the combination of an air tight tank, liquid therein, a combustion chamber, said combustion chamber communicating with said tank below the liquid level therein, and means for causing explosions in said chamber whereby the gas is transferred under pressure from said combustion chamber to said tank.

2. In a sprayer, the combination of an air tight tank, spraying liquid therein, a combustion chamber, said combustion chamber communicating with said tank below the liquid level therein, means for automatically

causing repeated explosions in said chamber whereby the gas is transferred under pressure from said combustion chamber to said tank.

5. In a sprayer, the combination of an air tight tank, a combustion chamber, a passage opening to said combustion chamber and to said tank below the level of the liquid therein, said passage being provided with an 10 aperture through its wall opening to said tank, and means for causing an explosion in said combustion chamber whereby the gas from said explosion chamber is caused to pass through said aperture into said tank.

15. 4. The combination of an air tight tank, an explosion chamber, a passage communicating with said explosion chamber and tank, a piston having inertia in said passage, means for producing an explosion in said 20 chamber to propel said piston toward said tank, and means for putting said combustion chamber into communication with said tank so as to cause the gas to pass from the explosion chamber to the tank after the explosion has occurred in said chamber and means for retracting said piston.

5. The combination of an air tight tank, an explosion chamber, a passage communicating with said explosion chamber and tank, a piston having inertia in said passage, means for producing an explosion in said 30 chamber to propel said piston toward said tank, an aperture through the wall of said passage communicating with said tank and adapted to be uncovered by said piston in its stroke under the impetus of said explosion and means for retracting said piston.

6. The combination of a receptacle adapted 40 to contain compressed gas, a combustion chamber, a communicating passage between said combustion chamber and receptacle, a piston having inertia adapted to reciprocate in said passage and in its motion toward said receptacle to open a passage for compressed 45 gas between said combustion chamber and said receptacle, means for causing an explosion in said chamber to propel said piston toward said receptacle, said piston being adapted to be forced back by the action 50 of said compressed gas whereby a charge of explosive mixture is drawn into the combustion chamber and compressed on said return stroke of said piston.

7. The combination of a receptacle adapted 55 to contain compressed gas, a combustion chamber, a communicating passage between said combustion chamber and receptacle, a

liquid in said receptacle, said passage being below the level of said liquid, means for causing an explosion in said combustion 60 chamber to propel the liquid in said passage toward said receptacle, the water being returned by the action of said compressed gas, and means whereby a passage for the gas between said chamber and receptacle is 65 established when the water in said passage moves toward said receptacle, whereby a charge of explosive mixture is drawn into the combustion chamber and compressed on said return motion of said water. 70

8. The combination of a receptacle adapted to contain compressed gas, a combustion chamber, a communicating passage between said combustion chamber and receptacle, a piston having inertia adapted to reciprocate 75 in said passage and in its motion toward said receptacle to open a passage for compressed gas between said combustion chamber and said receptacle, means for causing an explosion in said chamber to propel said piston 80 toward said receptacle, said piston being adapted to be forced back by the action of said compressed gas whereby a charge of explosive mixture is drawn into the combustion chamber and compressed on said return stroke of said piston, and automatic means for igniting the compressed charge in the combustion chamber.

9. The combination of a receptacle adapted to contain compressed gas, a combustion 90 chamber, a communicating passage between said combustion chamber and receptacle, a liquid in said receptacle, said passage being below the level of said liquid, means for causing an explosion in said combustion 95 chamber to propel the liquid in said passage toward said receptacle, the water being returned by the action of said compressed gas, and means whereby a passage for the gas between said chamber and receptacle is 100 established when the water in said passage moves toward said receptacle whereby a charge of explosive mixture is drawn into the combustion chamber and compressed on said return motion of said water whereby a charge of explosive mixture is drawn into the combustion chamber and compressed on said return motion of said water, and automatic means for igniting the compressed charge in the combustion chamber. 105 110

In testimony whereof, I sign this specification.

FRED S. WELCH.
